UNITED STATES PATENT OFFICE.

RALPH H. MANSON, OF PITTSBURGH, PENNSYLVANIA, ASSIGNOR TO HUBBARD AND COMPANY, A CORPORATION OF PENNSYLVANIA.

INSULATOR SUPPORT.

Application filed July 3, 1926. Serial No. 120,427.

This invention relates to insulator supports and more particularly to the type known as secondary racks such as are commonly used for mounting a row of insulators upon a supporting wall, pole or the like.

Supports of this type generally consist of a base section by means of which the device is secured to the supporting structure and on which are mounted a plurality of separately formed, outwardly extending insulator supporting arms, the latter being of a configuration dependent upon the particular type of insulator to be supported.

It has heretofore been customary to form the arms separately and secure them to a base section, which itself may be formed by one or more parts, by any suitable manner of fastening such, for example, as riveting.

It is apparent that this form of construction is subject to serious defects from the commercial viewpoint, there being, among others, the cost and time of manufacturing, due to the necessity of assembling the various separate parts and positioning them securely together. The strength of such devices is always largely dependent upon the strength of the particular fastening means employed rather than upon the design and construction of the completed rack.

An object of this invention is to provide an improved method of manufacturing insulator supports of the type set forth.

A further object is to provide a method of manufacturing devices of the type set forth from a single piece of metal.

A still further object is to provide a secondary rack which is formed from a single piece of metal and which eliminates objectionable features in the prior art racks known to me.

These and other objects which will be obvious to those skilled in this particular art are attained by means of this invention, one form of which is illustrated in the accompanying drawings, in which Figure 1 is a front elevation of a blank which has been formed from stock, such as sheet metal. Fig. 2 is a view in side elevation of the blank after being bent to form a finished rack and Fig. 3 is a section on the line 3-3 of Fig. 2, showing one of the insulator supporting arms in plan.

In applying the invention to the manufacture of the particular kind of supporting rack illustrated, a flat strip of sheet metal stock is

blanked out, preferably by stamping, to provide a blank of the form shown in Fig. 1, having parallel side members connected by a plurality of integral cross arms. The blank thus formed is seen to be symmetrical and one axis of symmetry coincides with the line passing through the centers of the cross arms parallel to the side members. By bending the blank back upon itself and about this line as a center the side members are positioned adjacent each other so as to form the base section of an insulator rack, the arms of which are integral therewith and formed by the bent cross arms of the blank.

In the illustrated embodiment of the invention, a flat metal sheet is stamped or otherwise cut to form a flat blank 5 having the configuration shown in Fig. 1. The blank includes parallel side members 6 connected by a number of integral spaced cross arms 7. Each cross arm has central notches 8 which form a central relatively narrow section 9 between relative wide sections 10 which taper gradually toward the side members 6. Slots 11 are punched adjacent the edges of the side members 6 preferably, but not necessarily, at the same time the blank is stamped from the sheet material.

It is obvious from an inspection of Fig. 1 that the blank is symmetrical with respect to the medial line drawn through the centers of the narrow sections 9 parallel to the side edges of the blank. The blank is next pressed in a forming die which bends the side members 6 downwardly along the dotted lines 13 to form right angle base flanges 12 and preferably at the same operation bends the edges of the wide portions 10 of the connecting arms upwardly along the dotted lines 14 to form top and bottom flanges 21 on the connecting arms. The blank is next formed about a mandrel engaging the central sections 9 of each connecting arm until the edges 21' of the flanges 21 of one side butt against the edges 21' of the flanges 21 of the outer side. This produces a substantially smooth surface on the tops and bottoms of the insulator supporting arms so that line wires can be dragged thereacross during the operation of stringing the wires without any danger of their being abraded by sharp edges on the arms. In bending the edges of wide portions 10 as described the edges of the slots 8 are so positioned that they cooperate with

the narrow sections 9 to form openings 15 in the outer ends of each of the finished arms for receiving the usual pin 16 on which the insulators 17 are mounted. One such insulator is shown broken away in Fig. 2. The blank is finished by securing the bent edges 21' together, preferably by spot welds 18 as illustrated in Fig. 3 or in any other desired manner.

- 10 The finished article comprises an insulator rack having a base section 19 formed by the flanged side members of the original blank and provided with outwardly extending insulator arms 20 which are an integral part 15 of the supporting base and which preferably taper gradually from their outer ends to the base. Being formed from a single piece of metal there are no fastening means and no separate parts to become loosened so as to 20 render the rack unusable. The present method materially increases the rapidity of manufacture as it eliminates the necessity for assembling different parts and securing them together, and the cost of manufacture is 25 consequently reduced. The entire bending of the blank shown in Fig. 1 to form the rack can be accomplished in a single step, after which it is only necessary to secure the edges 21' of the arms together.
- 30 In addition, the present invention provides a rack having no crevices or joints where moisture can collect and set up a galvanic action to destroy the galvanized coating where such coating is employed.
- 35 Although I have described a particular series of steps for manufacturing a single form of insulator support, it will be obvious that various changes, omissions, additions or substitutions can be made therein without departing from the spirit of this invention or 40 the scope of the appended claims.

What I claim as new and desire to secure by Letters Patent is:

1. The method of manufacturing insulator supports which consists in providing a blank having longitudinally extending side members connected by a plurality of integral connecting arms, and bending the blank to form an insulator supporting rack. 45
2. The method of manufacturing insulator supports which consists in forming a blank having side members connected by a plurality of integral connecting arms, bending the blank about the centers of said arms so that said side members are adjacent each other to 50 form a base section having a plurality of insulator supporting arms integrally formed thereon. 55
3. The method of manufacturing insulator supports which consists in stamping a metal sheet to form a symmetrical blank having side members joined by a number of integral cross arms, bending the blank along one axis of symmetry until said side members are adjacent each other and flanging the side members 60 to form a base having a plurality of outwardly extending arms. 65
4. The method of manufacturing insulator supports which consists in stamping a metal sheet to form a symmetrical blank having 70 side members joined by a number of integral cross arms, bending the blank along one axis of symmetry until said side members are adjacent each other, flanging the side members to form a base having a plurality of outwardly extending arms and bending the edges of the arm blanks into substantial engagement with each other. 75

In testimony whereof, I have hereunto subscribed my name this 26th day of June, 1926.

RALPH H. MANSON.
